STERLING G. SEARS, OF BROOKLYN, NEW YORK, ASSIGNOR TO NAYLOR RADIO CORPORATION, A CORPORATION OF NEW YORK

BINDING POST

Application filed November 8, 1926. Serial No. 146,887.

This invention relates to improvements in binding posts.

Binding posts as heretofore made were usually composed of an axially-disposed screw on which was mounted a base portion having a flat surface and a clamping nut or head member threaded on the upper end of said axially-disposed screw and adapted to clamp wire against said surface surrounding said axially-disposed screw on the base portion. In most cases, the wire which it is desired to clamp, was wound around the axially-disposed screw member and the nut was screwed down home. The tendency was, however, to squeeze the wire off the base.

The main object of my invention is to improve the construction of binding posts to the end that the wire instead of having a tendency to be squeezed off the base will have a tendency to move toward the axial member and thus to be more tightly clamped in place and in fact to cause the connecting wire to be firmly held between the clamping members.

Preferably my invention consists in the provision in the clamping surface of the base member of a slightly depressed and preferably conical depression. This slightly conical depression causes the wires to be clamped to have a tendency to move toward the center or the lower portion of the depressed surface and, therefore, to be more firmly clamped in place. The making of this conical depression, however, produces at the perimeter of the clamping seat of this base member, a relatively sharp edge which under normal circumstances with a nut of the same dimensions would be likely to cut into that portion of the connecting wire which passes off the base and I preferably provide means for preventing this cutting of the wire by the relatively sharp edge or rim thus formed and in the preferred embodiment of my invention I preferably reduce the diameter of the nut contiguous to its base portion so that the perimeter of the clamping surface of the nut will engage the shank of the wire at a point out of registration with the perimeter of the base portion, thus avoiding a scissors action and a cutting of the wire at this point. The edge of the nut

may also be rounded so as to further prevent the cutting of the wire thereby.

With these and other objects in view, the invention comprises the combination of members and arrangement of parts so combined as to co-act and cooperate with each other in the performance of the functions and the accomplishment of the results herein contemplated, and comprises in one of its adaptations the species or preferred form illustrated in the accompanying drawings, in which:—

Fig. 1 is a vertical section through a binding post showing in full lines the clamping nut separated from the clamping base and also showing the closed position in dotted lines of the two parts;

Fig. 2 is a similar view showing the wire clamped between the nut and the base member; and

Fig. 3 is a section on the line 3—3 of Fig. 2, looking in the direction of the arrow.

Referring now to these drawings, which illustrate a preferred embodiment of my invention, 1 indicates a panel or the like on which my improved binding post is mounted and 2 indicates a central axial post member extending through a socket 1^a in the panel or support 1 and being provided at its lower end with suitable means such as a nut 3 for forming a connection with a conductor 4 and also mounting the post in the panel 1. Mounted on the axial post member 2 is a base clamping portion 5 which is provided with a depressed clamping surface 5^a. Said clamping surface is preferably of conical conformation. The member 2 is screw threaded at its upper end as shown at 2^a and mounted at the upper end thereof is a head or nut 6 adapted upon rotation to approach the depressed conical wire seat 5^a. The head or nut 6 is preferably provided with a clamping surface 6^a of less diameter than the surface 5^a and the edge or perimeter 6^b is preferably round.

In the preferred form of my invention shown, the nut portion is preferably irremovably connected to the axial member 2. In the preferred embodiment shown, the permanent connection between the member 2 and nut is preferably accomplished by providing at the upper end of the member 2 a surface which is

slightly cupped or provided with a depression and the nut is provided with a central socket 8 having a wall 9 of less curvature than the cupping of the end 7 of the screw member 2. This cupping of the screw member 2 weakens the perimetral portion and when the surface 9 is screwed down upon it, the perimetral edges thereof are squeezed outwardly so as to form a head 10 as shown in Fig. 2 and the perimetral portion 10^a will thus form a stop to prevent the removal of the nut from the screw.

In connecting the wire to the binding post, the end of the wire is wound about the central screw portion and the nut is screwed home. Because of the conical, depressed surface 5^a, the wire, instead of having a tendency to slip off the edge, will have a tendency to move inwardly toward the screw and will be tightly gripped. Furthermore, any cutting of the wire at the shank or that portion which passes over the edge or rim of the binding post will be prevented by preferably, first, making the clamping surface 6 of the nut of less diameter so that the perimeter thereof will not register with the somewhat sharpened perimeter of the surface 5^a and will afford greater space between the surfaces of the clamping members, and second, because of the rounding off of the perimetral edge of the nut, the cutting action in the downward movement of the nut will be avoided.

Having described my invention, I claim:—

A binding post embodying an axially-disposed screw portion, a base portion connected with said screw and a nut member arranged to cooperate with said base portion to clamp a wire therebetween, said base portion having a depressed surface inclining inwardly toward said axial member, said nut member having a perimeter reduced in diameter to cause its edge to be positioned opposite a portion of such clamping surface inward of the edge thereof.

In witness whereof, I have signed my name to the foregoing specification.

STERLING G. SEARS.
